UNITED STATES PATENT OFFICE.

FRIEND A. RUSS, OF GREENWICH, CONNECTICUT, ASSIGNOR TO THE ROBERT N. BASSETT COMPANY, OF SHELTON, CONNECTICUT, A CORPORATION OF CONNECTICUT.

GARMENT-SUPPORTER.

1,171,805.

Specification of Letters Patent. Patented Feb. 15, 1916.

Continuation of application Serial No. 654,783, filed October 14, 1911. This application filed February 25, 1913. Serial No. 750,507.

To all whom it may concern:

Be it known that I, FRIEND A. RUSS, a citizen of the United States, residing at Greenwich, in the county of Fairfield and 5 State of Connecticut, have invented a certain new and useful Improvement in Garment-Supporters, of which the following is a specification.

My invention relates to garment supporters but more particularly to the buckles used 10 in connection with the same.

The present application is a continuation of my prior application for buckles filed October 14, 1911, Serial No. 654,783, and is 15 also a continuation, in so far as it relates to the disclosure in Figures 1 to 4 inclusive, of my prior application for garment supporters filed December 6, 1910, Serial No. 595,858.

One object of my invention is to provide a 20 garment supporter in which the end of the supporting strap is swaged to the buckle so that the strap can not become separated therefrom when the lever is opened or upset.

Another object of my invention is to provide a buckle in which that portion of the 25 back coöperating with the lever edge is reinforced by a fold in the metal.

I attain these and other objects of my invention in the devices set forth in the following 30 description and accompanying drawings in which like reference characters refer to corresponding parts.

In the drawings: Fig. 1 is a front view of my device some of the parts being shown 35 broken away; Fig. 2, a vertical section taken through the center of the buckle shown in Fig. 1, the loop and webbing being shown in elevation; Fig. 3, a front view of the device shown in Fig. 1 before the lever is assembled; Fig. 4, a view showing the parts in the process of being assembled; Fig. 5, a front 40 view of a modification some of the parts being shown broken away; and Fig. 6, a vertical sectional view taken on the center line 45 of Fig. 5.

My device generally comprises the buckle frame or back A journaled across the front of which is the lever B. Hinged to the bottom of the back A is the button loop C. The 50 back A also carries the ends respectively of the tab D and the strap or webbing F, both of which are gripped by the back in a manner which will hereinafter be described. The tab D carries a button E which latter

coöperates with the loop C in the manner 55 usual in button clasps.

Referring to Figs. 1, 2, 3 and 4 the back A of the buckle is made out of sheet metal and comprises the plate 1 having the forwardly projecting side ears 2, 2 provided 60 with apertures 3, 3. The locking lever B is also made out of sheet metal and consists of the front portion or shield 4, the clamping edge 5 and the laterally projecting trunnions 6, 6 journaled in the apertures 3, 3 of the side ears. The back plate A is provided with a transversely disposed lip 13 which projects forwardly from the top side of the back A. In assembling the back A and supporting strap F this lip 13 is 65 folded downwardly against the front face of the back plate to confine and conceal the end 11 of the strap F. The folding down of the lip B in this manner strengthens the back and prevents it from bending or 70 springing when resisting the wedging action of the lever edge 5 and thereby the webbing is held more securely and will not slip when subjected to the severe strain incident to the prevailing style of hose supporters. The 75 lower extremity of the back plate 1 is provided with a projecting integral tongue 7 having a substantially straight edge 8. This tongue is struck up together with the back A to form an open socket 9 across the bottom 80 of the back plate 1.

In assembling the back A, loop C and tab D the end 12 of the tab D is placed in the open socket 9 and the top side 10 of the loop C is then sprung over the tongue 7 so that 90 the top side 10 rests in the open socket 9 on top of the end 12 of the tab and the sides of the loop embrace the sides of the tongue, as shown in Fig. 4. The tongue 7 is then 95 curled around the top side 10 to form the bearing for the loop, and the edge 8 swaged down against the back plate thereby securely gripping the end 12 of the tab, as shown in Fig. 2. The tab D is then folded 100 downwardly and forwardly over the front of the top side of the loop and its button end E threaded through the widened portion of the loop. The side ears 2, 2 are then bent toward each other, causing the apertures 3, 3 to embrace the trunnions 6, 6 respectively of the lever B.

The supporter may be shortened and lengthened by raising and lowering the

buckle on the strap or webbing F. When the device is assembled the strap F passes around the edge of the lip 13 straight up through the buckle, that is, between the lever B and the front face of the lip. In this position the supporter is of maximum length. To shorten the supporter, that is, to shorten the supporting portion of the strap, the running portion of the strap is pulled or pushed downwardly through the buckle causing the lower portion of the strap to form a slack loop as shown in Figs. 1 and 2. Of course it is understood that the lever is upset or opened during the time the strap is being passed up and down through the buckle, and that when the proper adjustment of the strap is effected the lever is shut down or closed. The loop in the supporting strap above referred to may be sufficiently short so as to be entirely concealed behind the lever B, or may be sufficiently long so as to completely cover the button loop C, its length being determined by the amount of take up in the supporting strap. The clamping action of the edge 5 of the lever B in locking the supporting strap F against the back plate 1 serves to press the front portion or shield 4 against the loop formed in the supporting strap and hold the folds of the latter in close engagement with each other and against the curled tongue 7. This gives the device a flat and compact appearance. The principal advantage of my invention, however, resides in the feature of making the lower end of the supporting strap fast to the buckle thus avoiding the inconvenience and confusion resulting in the strap and buckle becoming separated, which often happens in that style of the device now on the market in which the end of the strap is free and not attached to the buckle. This separation not only occurs during the time of shipment, when the lever is accidentally upset, but also while the device is being manipulated on the person of the wearer.

It should be noticed that all of the parts are so designed and arranged as to be capable of the most rapid processes of assembling, and that no sewing or stitching is required since all the fabric parts are made fast by folding portions of the sheet metal back plate. It should be further noticed that the back plate 1 is a connecting piece for the loop, tab and the supporting strap, so that without the action of the lever the device may perform the function of a garment supporter in which there is no adjustment and in which the parts are all permanently fastened together.

My invention is not confined to the particular manner of fastening the strap and tab ends above described since these ends may be secured in various ways, one modification being shown in Figs. 5 and 6, in

which the top of the back A is not provided with any lip, and the extremity 11' of the supporting strap F is fastened under the tongue 7 which also fastens the extremity 12' of the tab and embraces the top side 10' 76 of the tab D in the same manner as above described. In this modification all of the parts with the exception of the lever B' are assembled in one metal bending operation.

It is obvious that my invention is susceptible of such further modification as may fairly come within the scope of the appended claims.

Having now described my invention what I claim and desire to protect by Letters 80 Patent is:

1. A hose supporter comprising a buckle having a pivoted lever and a sheet metal back, a supporting strap passed between said lever and back and having its lower extremity swaged to said back, and a garment fastening loop attached to said back, the edges of said back being folded to permanently secure all of said parts together, whereby all of the parts are assembled by 90 metal bending operations and none of the parts can become separated from the back when the buckle is open.

2. In a hose supporter buckle having a pivoted lever and a sheet metal back, and a supporting strap passed between said lever and back, the said back being provided with vertically disposed and forwardly turned side ears and having its upper extremity folded downwardly to form a reinforcing 100 lip between which and the body of the back is confined the end of the supporting strap, and the said lever being journaled between said ears so that its clamping edge will 105 contact with the front side of the reinforced portion of the back to lock the moving portion of said supporting strap when the buckle is closed.

3. As an article of manufacture a hose supporter comprising a supporting webbing, 110 a buckle having a pivoted lever and a sheet metal back, and a button clasp attached to said back, the said buckle having the upper edge of that portion of the back which contacts with the lever edge folded downwardly 115 to form a transversely disposed reinforcing lip between which latter and the body of the back is confined the end of the supporting webbing.

4. The combination with a hose supporter 120 comprising a supporting strap, a button loop and a button tab, of a buckle provided with a sheet metal back having forwardly turned side ears between which is journaled a pivoted lever, the said back having its lower 125 portion folded around the top side of said loop and its edge swaged down on to the end of said tab, and the said back having an edge folded and swaged down on to the end of said strap to permanently secure the same 130

to the back, whereby all of the parts can be assembled by metal bending operations and none of the parts can become separated from the back when the buckle is open.

5 5. In a hose supporter a buckle having a pivoted lever and a sheet metal back, and a supporting strap passed between said lever and back, the said back having its upper edge folded downwardly to form a reinforcing lip between which and the body of the back is swaged the end of the supporting strap, and the said lever being arranged to co-act with the front face of said lip to lock the moving portion of said supporting strap

15 when the buckle is closed.

6. In a hose supporter a buckle having a pivoted lever and a sheet metal back, and a

supporting strap passed between said lever and back, the said back being provided with vertically disposed and forwardly turned 20 side ears and having its upper edge folded downwardly between said ears to form a reinforcing lip between which and the body of the back is swaged the end of the supporting strap, and the said lever being journaled between said ears so that its clamping edge will co-act with the front face of said lip to lock the moving portion of said supporting strap when the buckle is closed. 25
